UNITED STATES PATENT OFFICE

JAMES L. ARTHUR, OF ANDERSON, INDIANA, ASSIGNOR TO DELCO-REMY CORPORATION, OF ANDERSON, INDIANA, A CORPORATION OF DELAWARE

IGNITION APPARATUS

Application filed December 11, 1931. Serial No. 580,279.

This invention relates to ignition apparatus for internal combustion engines and more particularly to the control of the timing of the ignition in response to engine operating conditions and particularly in response to suction in the fuel intake passage of the engine.

In some types of engines it is desirable to advance the spark quickly when moving the throttle from engine idling position to a part throttle position in order that the engine may operate more economically. However, when cranking the engine with the throttle partly open, it has been found desirable to retard the ignition in order that back-firing may not occur. It is an object of the present invention to provide a suction operated ignition timer control which will advance the spark during engine operating conditions but which will not advance the spark while cranking the engine.

Further objects and advantages of the present invention will be apparent from the following description, reference being had to the accompanying drawing wherein a preferred embodiment of one form of the present invention is clearly shown.

In the drawing:

The figure of the drawing is a diagram illustrating the present invention.

Referring to the drawing, the ignition circuit comprises a coil 20 having a primary 21 and a secondary 22, the primary being connected with a battery 23 through a switch 24. The battery is grounded at 25. The primary 21 is connected by wire 26 with a terminal 27 connected by a leaf spring conductor 28 with a circuit breaker lever 29 pivoted on a post 30 carried by a circuit breaker lever plate 31 rotatable about the axis of the shaft 32 which drives a cam 33. The cam 33 cooperates with a rubbing block 34 which is connected with the spring 28, attached to the lever 29. The lever 29 carries a contact 35 which cooperates with a grounded contact 36. The plate 31 has an arm 40 connected by a pin 41 with a rod 42 which is provided with an extension 43 of reduced diameter which provides a rivet to which are attached to the rod 43 two oppositely arranged cup-shaped washers 45 and

44 and a flexible diaphragm 46 located between them. The circular edge of the diaphragm 46 is pinched between flanges 47 and 48 of suction chamber housing members 49 and 50 respectively. The flange 48 is bent over at 51 to engage the flange 47. The member 49 provides a sleeve 52 serving as a guide for the rod 42 and has a vent hole 49a. The member 50 carries a tubular bushing 53 which locates one end of the spring 54, the other end being located by the washer 45. The spring 54 tends to keep the diaphragm 46 in a position for retarding the spark, the direction of retarding movement of the arm 40 being indicated by the arrow 55. The cam 33 rotates counterclockwise as indicated by arrow 56.

The tubular bushing 53 is connected by pipe 60 with a valve body 61 which provides a central vertical passage 62 and side passages 63, 64 and 65, the passage 63 continuing from the pipe 60. The passage 64 is connected by passage 66 with the passage 67 in a carburetor passage 68 and located just below the throttle valve 69 when in engine idling position as shown in the drawing.

The carburetor passage 68 is provided with a venturi 70 surrounding a fuel nozzle 71 connected with a fuel bowl 72. The passage 65 is connected by a pipe 73 with a passage 74 in the carburetor passage 68, the passage 74 being located inside the carburetor choke valve 75. The communication between the passages 63 and 64 in the valve body 71 is controlled by a vertical slide valve 80 having a circumferential groove 81 located between flanges 82 and 83 which provide bearings for the valve 80. The valve 80 is urged upwardly against the cross pin 84 by a spring 85 held in position by a screw block 86.

When it is desired to accelerate the engine from idling the valve 69 is opened to a position such as 69a thereby increasing the suction at the pipe 67 and thereby decreasing the pressure below the diaphragm 46 whereby the diaphragm will move into the dot-and-dash line position 46a to advance the spark to a greater extent than might be possible with a known form of speed responsive advance mechanism, (not shown) with which ignition timers are now usually provided.

- When cranking the engine however with the throttle partly opened as indicated by the position 69a of the throttle 69, it may not be desirable to advance the ignition to greater than the extent provided by the centrifugal advance mechanism. Since it is the usual practice to choke the carburetor when cranking the engine, advantage is taken of the fact that during cranking with the choke 5 closed, there is a substantial suction in the carburetor pipe 68 inside of the choke valve 75. When the valve 75 is closed as shown in the diagram, there will be a substantial reduction in pressure in the pipe 73, and this subatmospheric pressure is communicated to that 10 part of the passage 62 of valve body 61 below the valve 80. Consequently the valve 80 moves downwardly against the resistance of the spring to close off communication between the passages 64 and 63. Hence, during the cranking of the engine with the carburetor choke valve 75 closed, the suction device will not operate to advance the ignition 15 although the throttle valve 69 may be in a partly open position while cranking. When the choke is closed, part 63 is immediately vented to relieve any vacuum below diaphragm 50; and the spark will be immediately retarded. 20 As soon as the engine fires, the operator will generally release the choke control knob to permit the choke valve to move by a spring (not shown) to the normal open position 75a. Immediately the suction at opening 75 will 25 decrease and the spring 85 will return the valve 80 to the position shown, whereupon the suction device will be operative to advance the spark when the valve 69 is opened. 30 While the form of embodiment of the present invention as herein disclosed, constitutes a preferred form, it is to be understood that other forms might be adopted, all coming within the scope of the claims which follow. 35 What is claimed is as follows:
- 40 1. Ignition apparatus for internal combustion engines comprising, in combination, a carburetor having an air choke valve and a fuel throttle valve, a circuit interrupter, an engine driven cam for operating the interrupter, a device responsive to engine suction for controlling the angular relation between the interrupter and cam in order to control the timing of the ignition, and means responsive to closing the choke valve of the carburetor and operated by suction in the carburetor between said valves for preventing the operation of the suction device to control the ignition timing. 45 2. Ignition apparatus for internal combustion engines comprising, in combination, a carburetor having an air choke valve and a fuel throttle valve, a circuit interrupter, an engine driven cam for operating the interrupter, a device having communication with the carburetor and responsive to engine suc-

tion for controlling the angular relation between the interrupter and cam in order to advance the ignition timing as the throttle valve is opened, and a suction operated valve responsive to the closing of the choke valve 75 and operated by suction in the carburetor between its said valves for closing off communication between the suction operated controlling device and the carburetor.

In testimony whereof I hereto affix my signature. 75

JAMES L. ARTHUR.
